TENSION MECHANISM

Charles S. Caffrey, Port Washington, N. Y., assignor to Wood Newspaper Machinery Corporation, Plainfield, N. J., a corporation of Virginia

Application January 24, 1942, Serial No. 428,133

7 Claims. (Cl. 242—58)

My invention is described here as relating to improvements in machinery for supplying rolls of paper to printing presses and the like under definite control of tension. Specifically my invention is in a web tension mechanism by which the normal tension on a web of newsprint paper can be maintained as it is fed from an unwinding reel. It is conventional practice to feed a web of newsprint paper until the supply of one reel is depleted whereupon the web is spliced to one on a fresh reel and the feeding continued with a minimum of slackening or interruption. Generally the tension of the web on an unwinding reel has been held to the desired amount by having the reel or roll contact travelling belts driven by the printing press at a speed approximately two percent below the speed of the web and thus governing the tension of the latter by the tightness of the belt. Full speed web roll changers are also in general use for semi-automatically splicing on a fresh roll before the unwinding roll is depleted. When the tension of the running belt and the web roll changer are used together it becomes desirable and even necessary to stop the running belts during the change in rolls, holding the tension of the web in this case by the tightness of the belts which have been brought to stationary positions. Experience has shown that stopping these belts causes a sudden increase in the tension of the web frequently causing the paper to tear under the belts. It is to prevent this difficulty that my improved mechanism which will be described is intended.

A further object of my invention is to maintain a normal desired tension on the web during its feeding from the reel regardless of the extent to which the unwinding diminishes the diameter of the roll.

A further object of my invention is to provide means to bring the tension on the web back to normal if it becomes either too great or too small.

A still further object of my invention is to provide means for controlling the tension of the running belts from the degree of tension existing at that moment in the web being fed.

Among the objects of my invention is the further one of automatically slackening the tension of the running belts and finally stopping their travel entirely during the period when the web from a reserve roll is being spliced to the end of a depleted roll.

The accompanying drawings illustrate in diagrammatic form and by way of example only,

the preferred embodiment of my invention. In the drawings

Fig. 1 is a diagrammatic side view in elevation of my improved web tension mechanism as applied to the conventional newsprint magazine reel, brush and knife arm, running belt, tension equipment and floating roller;

Fig. 2 is a similar side view with a driving clutch, brush and knife arm and floating roller in the position for making semi-automatic roll changes and

Fig. 3 is a simplified diagram of the pneumatically operated mechanism for controlling the tightness of the running tension belts from the floating roller.

Briefly described, my invention consists first in provision for using the variation in tension of the web being fed to control the tension of the running belts upon that web thus bringing the tension of the web back to the normal desired amount. Incidental to this the drag of the travelling belts is first slackened and then the belts are stopped whenever the web is spliced. This gives a desired slackening to the web tension and makes the latter dependent upon the interruption or resumption in the movement of the running belts.

The drawings show the usual main supporting shaft 4 for a magazine reel. This reel has spiders 5 each with three equally spaced arms which in turn form journals for the rolls of newsprint paper. The roll from which paper is being unwound is shown at 6 as it approaches the completion of the unwinding operation and in position to be replaced by one of the reserve rolls 7, 8.

The web of paper 9 as it leaves the unwinding roll 6 passes over the bending roller 10. It then passes around the floating roller 33 on its way to the web printing press.

The tension by which the web 9 is held in its movement is controlled by a series of running belts of which one only is illustrated at 11. These belts run over idle pulleys 12, 13 and 14, in a counter-clockwise direction and at the desired speed. As above indicated this is generally slightly below the speed of the web as called for by the press. A tension pulley 15 is provided to control the tension of the belts 11. The travel of the belts is accomplished by drive roller 16 the shaft of which has a miter gear 17.

A corresponding miter gear 18 is mounted on shaft 19. The upper end of shaft 19 carries a miter gear 20 in mesh with miter gear 21 on shaft 22.

Shaft 22 is journalled in standards 23 and 24. A sprocket wheel 25 turns loosely upon shaft 22 and is driven by means of sprocket chain 26 from the printing press.

Sprocket wheel 25 has a clutch member 27.

The standard 24 has a brake member 28 fastened thereto and concentrically surrounding shaft 22.

Intermediate the clutch member 27 and the brake 28 there is a clutch member 29 keyed upon shaft 22 for sliding movement into contact with either the clutch 27 or the brake 28.

This clutch is operated by means of a clutch collar 30 engaged by trunnions 31 on the shift lever 32. In normal operation during the running of the roll clutch members 27 and 29 are held in engagement and travelling belts 11 are driven at the desired speed by power from the sprocket chain 26. When the clutch lever 32 is shifted to the left of Figure 1 clutch member 29 is first separated from clutch member 27 so that the latter ceases to rotate shaft 22. Completion of the movement brings clutch 29 in engagement with brake 28 thus holding the belts 11 stationary, as shown in Fig. 2.

From the bending roll 10 the web passes around a floating roller 33. This roller is journalled on a rock arm 34 fastened to rock shaft 35 suitably journalled in fixed bearings. The rock shaft 35 carries a weight arm 36 having a suitable adjustable weight 37 along the arm 36 and varies the tension of the web 9 in opposition to the drag from the printing press.

Rock arm 34 is designed to have a normal vertical position from which it may oscillate some twenty degrees in either direction under the joint influence of the drag from the printing press and the opposing weight 37.

Rock shaft 35 carries a cam 38. Opposite the cam is an air valve 39, the plunger 40 of which rests in contact with the face of the cam 38. In this way the degree of opening the air valve 39 is controlled by the position of the rock arm 34 and thus indirectly affected by the tension of the web 9. Movement of the rock arm 34 to the right as seen in Fig. 1 which would result when the web becomes slack and the weight 37 causes the floating roller to move to the right, serves to open air valve 39 allowing air to pass from the supply to a suitable tension adjusting means for the travelling belts 11. Conversely when the tension of the web becomes too tight causing the floating roller 33 to move to the left, then valve 41 shuts off the air supply and lessens the tension on the running belts 11 so that they do not retard the unwinding movement as they normally would.

In starting the feeding of web 9 there would of course be moderate fluctuations encountered causing oscillation of the arm 34 and consequent opening and closing movements of the air valve until the tension has become steady at the desired degree.

The adjustable tension device 41 consists of an air chamber 42 fed by the air pressure from valve 39. A plunger 43 depending from the air chamber 42 carries the tension roller 15. Thus opening the air valve 39 increases the downward pressure on the tension roller 15 but closing the air valve will relieve the pressure on the tension roller 15 and the consequent tension of the belts 11.

Slackening of the tension from the travelling belts 11 and ultimate stoppage of the latter is desired whenever the web 9 is to be spliced to the

web of a reserve roll 7 or 8 and simultaneously disconnected from the depleted roll 6. To carry out this operation the shaft of the idle roller 13 forms a loose journal for a knife arm 44. This 5 arm has the usual brush 45 and cutter 46 which operating between the belts 11 serves to attach the web 9 to the corresponding web on roll 7 and simultaneously cut the web 9 between the point of attachment and the spindle of roll 6. 10 During this operation further rotation of the roll 6 would be objectionable as unwinding paper onto the floor or up into the mechanism. However, this can be prevented by stopping the travelling belts 11 during the splicing operation. It 15 is desirable to avoid causing a momentary strain on the web by stopping the belts too suddenly. This can be avoided by slackening the belts prior to stopping them. To accomplish this brush arm 44 has an opposite extension 47 pivotally connected to a rod 48 forming a link connection with the shifting lever 32 of the clutch and brake. 20 Thus when the arm 44 is lowered to make the change in the rolls, the clutch is first disconnected, causing a slackening in the drag of the 25 belts 11 and finally stopping the latter when the brake members 28 and 29 engage.

Pivots secured to arm extension 47 is a second link or rod 49 which passes through the rock arm 34. Stops 50, 50 provide desired degree of lost motion between the link 49 and the rock arm 34. These stops, however, are so adjusted that when the knife arm 44 is lowered, the arm extension 47 and the floating roller 33 are pulled to the left. This closes air valve 39 causing air pressure to the belt tightening cylinders 42 to be reduced. In this way lowering the knife arm 44 simultaneously slackens the tension on the belts and stops their travel. Furthermore when the knife arm 44 is raised after the splice 40 is completed, the belts are then set running and air pressure to the chamber 42 restored under the automatic control of the floating roller 33.

From the above description it will be evident that I have provided an arrangement by which 45 the pull exerted by the printing press upon the web of paper being fed is opposed by a normal tension and any variation in the pull provides a corresponding variation in the tension exerted on the web at the point where it leaves the roll. 50 When the pull becomes abnormally great, tension on the web is lessened and vice versa until the normal desired pull is restored. This arrangement also compensates for differences caused by the degree by which the supply of paper is removed from the roll.

In addition the drag of the tension belts is first slackened and then the travel completely stopped incidental to the splicing operation carried out by the knife and brush arm. Conversely 60 restoring this arm's position to normal throws into operation the feed of the web at the normal desired tension. The new roll 7 must be rotated into the normal running position in contact with belts 11 before the web tensioning means will 65 operate in its normal manner.

The several details of the mechanism are subject to change and variation without departing from the scope of the invention as set out more particularly in the appended claims.

What I claim is:

1. In combination with a roll of paper and a bending roller receiving a web from said roll, a rock arm, a floating roller carried by the arm for receiving the web from the bending roller, a rock shaft carrying the arm, a counter-weight

on the shaft, a cam on the shaft, a fluid pressure valve controlled by the cam, a running tension belt bearing on the roll of paper, driving means for the belt, a tension roller resting by gravity on the belt, a vertical piston above the roller and upon which the roller is journaled, a fluid pressure chamber for urging the piston downwardly against the belt and means connecting said chamber with the pressure valve.

2. In combination with a roll of paper and a bending roller receiving a web from said roll, a rock arm, a floating roller carried by the arm for receiving the web from the bending roller, a rock shaft carrying the arm, a counter-weight on the shaft, a running tension belt bearing on the roll of paper, a driving roller for the belt, gearing for said driving roller, a tension roller for the belt, fluid pressure means for exerting pressure from the tension roller to the belt, a cam on the rock shaft, means actuated thereby to supply said fluid pressure means, and common means for interrupting the drive through the gearing and for diminishing the fluid pressure supply.

3. In combination with a roll of paper and a bending roller receiving a web from said roll, a rock arm, a floating roller carried by the arm for receiving the web from the bending roller, a rock shaft carrying the arm, a counter-weight on the shaft, a cam on the shaft, a fluid pressure valve controlled by the cam, a running tension belt bearing on the roll of paper, driving means for the belt, fluid pressure operated means for changing the bearing action of the belt on the roll, means connecting the last mentioned means with the fluid pressure valve, said belt driving means including a clutch, a pivoted knife arm and means actuated by said knife arm to release the clutch and close the fluid pressure valve when the knife arm approaches the web.

4. In combination with a roll of paper and a bending roller receiving a web from said roll, a rock arm, a floating roller carried by the arm for receiving the web from the bending roller, a rock shaft carrying the arm, a counter-weight on the shaft, a cam on the shaft, a fluid pressure valve controlled by the cam, a running tension belt bearing on the roll of paper, driving means for the belt, fluid pressure operated means for changing the bearing action of the belt on the roll, means connecting the last mentioned means with the fluid pressure valve, said belt driving means including a clutch, a pivoted knife arm,

linkage from the knife arm to the clutch, and separate linkage from the knife arm to the rock arm.

5. In combination with a roll of paper and a bending roller receiving a web from said roll, a rock arm, a floating roller carried by the arm for receiving the web from the bending roller, a rock shaft carrying the arm, a counter-weight on the shaft, a cam on the shaft, a fluid pressure valve controlled by the cam, a running tension belt bearing on the roll of paper, driving means for the belt, fluid pressure operated means for changing the bearing action of the belt on the roll, means connecting the last mentioned means with the fluid pressure valve, said belt driving means including a clutch, a pivoted knife arm, linkage from the knife arm to the clutch, separate linkage from the knife arm to the rock arm and a lost-motion connection between the rock arm and the second mentioned linkage.

6. In combination with a roll of paper and a bending roller receiving a web from said roll, a rock arm, a floating roller carried by the arm receiving the web from the bending roller, a rock shaft carrying the arm, a counterweight on the shaft, a cam on the shaft, a fluid pressure valve controlled by the cam, a running tension belt bearing on the roll of paper, fluid pressure operated means for changing the tension in the belt, means connecting said fluid pressure operated means with the valve, belt driving means for the belt, including a clutch, and means for simultaneously arresting the travel of the belt and reducing its tension on the web.

7. In combination with a roll of paper and a bending roller receiving a web from said roll, a rock arm, a floating roller carried by the arm receiving the web from the bending roller, a rock shaft carrying the arm, a counter-weight on the shaft, a cam on the shaft, a fluid pressure valve controlled by the cam, a series of tension belts bearing on the roll of paper, fluid pressure operated means for changing the tension in the belts, means connecting said fluid pressure operated means with the valve, belt driving means for the belt including a clutch, a knife arm operating between said belts, and means actuated by the knife arm for simultaneously arresting the travel of the belts and reducing their tension on the web.

CHARLES S. CAFFREY.
